his Atty's.

UNITED STATES PATENT OFFICE.

CHARLES TWEEDIE, OF JEFFERSON CITY, MISSOURI.

DESIGN FOR AN ANKLET.

59,044.

Specification for Design.

Patented Sept. 13, 1921.

Application filed January 7, 1921. Serial No. 435,752. Term of patent 14 years.

To all whom it may concern:

Be it known that I, CHARLES TWEEDIE, a citizen of the United States, and a resident of Jefferson City, county of Cole, and State of Missouri, have invented a new, original, and ornamental Design for an Anklet, of which the following is a specification.

In the accompanying drawing, which forms part of this specification,

The figure is a perspective view of an anklet embodying the design.

I claim:

The ornamental design for an anklet, as shown.

CHARLES TWEEDIE.
